UNITED STATES PATENT OFFICE.

GARRET S. MOTT, OF PHILADELPHIA, PENNSYLVANIA.

ELECTRICAL-SIGNAL TRANSMITTER.

SPECIFICATION forming part of Letters Patent No. 252,242, dated January 10, 1882.

Application filed November 17, 1881. (No model.)

To all whom it may concern:

Be it known that I, GARRET S. MOTT, a citizen of the United States, residing in Philadelphia, Pennsylvania, have invented certain Improvements in Electrical-Signal Transmitters, of which the following is a specification.

The object of my invention is to construct a simple yet efficient instrument for transmitting electrical signals on fire-alarm, district, and similar telegraph lines; and this object I attain by combining with a break-plate to be moved by the operator two arms to throw a pivoted weighted contact-piece into and out of the path of the break-plate, according to the direction in which the break-plate moves, as more fully described hereinafter.

In the accompanying drawings, Figure 1 is a perspective view of my electrical-signal transmitter with the usual spring and gearing removed. Fig. 2 is a front view with the parts in their normal positions; Fig. 3, a similar view, showing the parts moved to the positions for giving the signal; and Fig. 4 is a side view of the instrument, showing the inclosing case in section.

The frame of the instrument in the present instance consists of two plates, A and A', connected together by rods *a* and secured to a base, B. To bearings in the frame is adapted the main axis or shaft D, to which is connected a spiral spring, E, tending to turn the shaft in a direction contrary to that pointed out by the arrows, Figs. 1 and 2. To the front end of the axis D is connected a crank-arm, D', by which the shaft and its connections may be operated when it is desired to give a signal. To this axis is also secured the break-plate F, whose periphery is provided with teeth of a number and size necessary for the required signal. Connected to this plate, or to the shaft carrying it, are two arms, *f f'*, in the present instance nearly at right angles to each other, for operating the weighted contact-lever, as described hereinafter. This contact-lever G is pivoted to a block, H, secured to but insulated from the plate A, and is provided with a contact-finger, *g*, and a weight, *g'*. When the lever G is in its normal position the arm *g* rests on the block H, while, when the lever is thrown

over to bring the contact finger *g* into the path 50 of the break-plate, a projection on the lever G comes into contact with the stop *h* on the block, and the weight *g'* retains the lever in either position to which it is moved. The insulated block H is connected by the wire *h'*, preferably insulated, with the binding-post *p*, while the break-plate F through the frame is electrically connected to the post *p'*, so that when these posts are connected up in the usual manner the circuit will be closed and a signal given 60 at the central office whenever the contact-lever touches the break-plate F. The weight *g'* is provided with strips of insulating material at the points where the arms *f f'* come into contact with it, so that there may be no electrical connection between the weight and the arms.

The parts are shown in their normal positions in Fig. 2, with the circuit open, and when it is desired to give a signal the crank-arm D' 70 is turned in the direction of the arrow, Fig. 2, until the arm *f'* comes into contact with the weight *g'*, Fig. 1, and throws the lever over into the position shown in Fig. 3. Then, the crank-arm being released, the spring E, which 75 has been wound up by the turning of the crank, turns the shaft D and break-plate back in the opposite direction, and as it does so the contact-finger *g* comes into contact with the teeth on the break-plate, and each time it does so 80 completes the circuit and gives a signal at the distant station, until the arm *f* comes into contact with the weight *g'* again, tilts the lever G back to its normal position, Fig. 2, and stops the further revolution of the shaft D. 85

In order that the shaft D may not be rotated by the spring E too quickly to give distinct signals, it may be provided with an escape-movement, or may be geared down in any ordinary way, as shown in Fig. 4, for instance, 90 where the shaft D is shown geared down through the pinions 1, 2, 3, 4, 5, and 6 to the flier 7.

It will be readily understood that this instrument may be worked on a closed circuit instead of an open one, as described above.

I claim as my invention—

1. The combination of a movable shaft car-

rying a break-plate and arms with a pivoted contact-lever adapted to be tilted by the said arms into and out of the path of the teeth of the break-plate.

- 5 2. The combination of the frame, rotary shaft, carrying a break-plate, arms, and crank-handle, and a spring, with a pivoted contact-lever adapted to be thrown by said arms into and out of the path of the break-plate teeth, substantially as set forth.
- 10 3. The combination of a movable shaft car-

rying a break-plate and arms with a pivoted lever adapted to be operated by said arms, and carrying a weight and a contact-finger, as and for the purpose described.

15

In testimony whereof I have signed my name to this specification in the presence of two subscribing witnesses.

GARRET S. MOTT.
